UNITED STATES PATENT OFFICE.

HERBERT E. METCALF, OF SAN LEANDRO, CALIFORNIA, ASSIGNOR TO THE MAGNA-
VOX COMPANY, OF OAKLAND, CALIFORNIA, A CORPORATION OF ARIZONA.

VACUUM TUBE AND METHOD OF CONSTRUCTING THE SAME.

No Drawing.

Application filed July 23, 1924. Serial No. 727,707.

This invention relates to vacuum tubes such as are ordinarily used for rectifying and amplifying purposes, and as electric wave generators.

5 It is well known in the manufacture of vacuum tubes that certain substances which are commonly known as "getters" may be vaporized inside the vessel either during or after evacuation. This vaporization aids in 10 clearing up residual gases left in the vessel, by chemical combination, physical absorption, or by blanketing or enclosing gas molecules.

15 Such substances as are commonly in use include chemicals such as red phosphorus, metals such as magnesium, or a combination of several.

20 It is the usual procedure to insert such "getters" either as a coating on the various electrodes of the evacuated vessels, or in the case of metals, to affix them by welding, or some similar method, and vaporizing them by means of heat.

25 It is also well known in the art that these "getters" have a selective clean-up effect; that is, certain metals or substances being able to clean up, absorb, or otherwise rid the vessel of a certain gas, others of another gas.

Heretofore all such substances have either 30 been inserted into the vessel as an element or attached to an electrode. However, I have found a new and useful method of obtaining the same results by the use of an electrode formed of the material known to 35 the trade as "German silver". German silver is an alloy of zinc, copper, and nickel. In the present invention I provide an evacuated vessel having contained therein one or more electrodes composed of commercial 40 German silver.

The vacuum tube is constructed with the desired number of electrodes, according to the purpose it is to serve. One or more of these electrodes, preferably the cold anode 45 or the so-called grid or control electrode, or both, is formed of German silver.

Upon heating one or more of the electrodes of my device by any of the many ways well known in the art, during evacuation 50 a dissociation of the German silver

takes place, whereby part of the copper and part of the zinc distills off at certain temperatures, and is deposited on the walls of the tube in the form of a film. The nickel remains behind, and the mechanical strength of the electrode is unimpaired.

The film of copper and zinc which is dissociated from the German silver acts as a selective "getter" as it cools. The vessel is sealed while this film is still hot, and the absorption of the desired gases raises the vacuum after sealing.

It is of interest to note that in my method the copper and zinc are deposited separately on the walls of the vessel, parts of which 65 show a bright copper-red sheen, and other parts showing the silvery zinc color. In certain parts of the vessel, however, the copper and zinc seem to re-alloy, and have the characteristic luster of brass.

70 It is evident from the high clean-up of gases after sealing that several different gases are absorbed; just which ones I am not yet prepared to state. I do know, however, that this method gives a strong, effective 75 clean-up, sufficient to give proper operation of a hot cathode—cold anode device, even when an indifferent vacuum is present at the moment of sealing.

75 What I claim as new and desire to secure 80 by Letters Patent is:

1. A method of constructing a vacuum tube which consists of forming one of the electrodes of German silver and heating said electrode to throw off the copper and zinc component of the German silver and depositing the same upon the walls of the tube, the remaining constituents of the German silver, principally nickel, being left 85 in place to form an electrode.

90 2. A three-electrode vacuum tube composed of a hot cathode, a control electrode and an anode, one of the electrodes being composed of commercial German silver which has been heated to the point where 95 copper and zinc are deposited on the walls of the tube before sealing, and the nickel is left in place to form an electrode.

HERBERT E. METCALF.
